CLAIM

The ornamental design for an automotive exterior fender vent, as shown and described.

DESCRIPTION

FIG. 1 is a left side view of an automotive exterior fender vent in accordance with the present design, wherein the right side view of the fender vent is a mirror image thereof;

FIG. 2 is a front elevation view thereof;

FIG. 3 is a rear end/left side perspective view thereof; and,

FIG. 4 is a front end/left side perspective view thereof.

The second embodiment is a mirror image of the automotive exterior fender vent as shown in FIGS. 1-4.

In the drawings, the broken lines depict portions of an automobile that form no part of the claim.
